UNITED STATES PATENT OFFICE

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed October 29, 1929. Serial No. 403,196.

My invention relates to railway traffic controlling apparatus, and particularly to apparatus of the type comprising a tripping device located in the trackway and arranged to 5 co-operate with governing means carried on the train.

I will describe one form of tripping device embodying my invention, and will then point out the novel features thereof in claims.

10 In the accompanying drawings, Fig. 1 is a plan view of the device embodying my invention illustrating the relative positions of the parts with respect to a track rail. Fig. 2 is an end view of the structure shown in Fig. 1. 15 Fig. 3 is a top plan view of the tripping device shown in Fig. 1, with the cover removed. Fig. 4 is a vertical longitudinal sectional view taken on line IV—IV of Fig. 3. Fig. 5 is a fragmentary longitudinal sectional view of 20 a portion of the structure shown in Fig. 4 illustrating the manner in which the spring 23 is compressed to facilitate the removal thereof. Fig. 6 is a vertical transverse sectional view taken on line VI—VI of Fig. 3. 25 Fig. 7 is a view partly in elevation and partly in longitudinal section taken on line VII—VII of Fig. 6. Fig. 8 is an enlarged fragmentary view of the trackway trip arm showing the means for mounting it on the operating shaft and for varying its length. Fig. 30 9 is a view, partly in side elevation and partly in section, of the structure shown in Fig. 8.

Similar reference characters refer to similar parts in each of the several views.

35 Referring to the drawings, and particularly to Figs. 1 and 2, my invention is shown in connection with a trackway tripping device comprising a housing 1 which contains the mechanism for actuating the device and 40 which is mounted on the ties 2 of the trackway adjacent one of the rails 3. A rockshaft 4 is journaled in bearings 5 and 6 provided in the housing 1 (Fig. 6) and extends outwardly therefrom and is connected with one 45 end of an extension shaft 7 by means of a

coupling 8. The other end of the shaft 7 is journaled in a bearing bracket 9 which is mounted on the ties 2 on the opposite side of the rail 3. A trackway trip arm 10 is secured to the shaft 7 adjacent the rail 3 over 50 which traffic is to be controlled by the tripping device, and is adapted to be swung by mechanism presently to be described, between a substantially horizontal inoperative position and a substantially vertical effective 55 position in which it is illustrated in the drawings and in which it lies in the path of, and may set in operation, suitable train carried governing means, such, for example, as the lever of a valve in the air line controlling 60 the application of the brakes.

Referring to Fig. 4, a segmental gear 11 is fixed to the shaft 4 between the bearings 5 and 6 (Fig. 6) and meshes with a rack bar 12 provided at one end with a substantially 65 spherical head 13. This rack bar is shifted in one direction in order to rock the shafts 4 and 7 and swing the trip arm 10 to an inoperative position, by means of fluid pressure admitted to a cylinder 14 through a pipe 70 15 which is connected with the head 16 of the cylinder 14 and which leads to a suitably controlled source of pressure. The cylinder 14 is threaded into an opening provided in the housing 1 with the inner end thereof abutting a ring 17 which is also threaded into the opening and which is secured against displacement therein by a dowel screw 18. A piston 19 is mounted for reciprocation 75 within the cylinder 14 and is formed on its inner face with a reentrant seat 20 for engagement with the spherical head 13 of the rack bar 12. The piston is prevented from becoming displaced from the rack bar 12 by 80 means of a washer 21 which surrounds the bar 12 and the opening in which is of smaller diameter than the spherical head 13. The washer 21 is held in position adjacent the head 13 by means of a resilient wire band 22 85 90

which seats within a groove provided in the piston 19.

The rack bar 12 is normally biased to the right, as viewed in Fig. 4, in order to hold the trip arm 10 in an upright operative position, by means of a spring 23. This spring is disposed within a cylindrical casing 24 which is arranged in axial alignment with the fluid pressure cylinder 14, and which is threaded 10 into an opening formed in the housing 1 with its inner end abutting a ring 25. This ring is also threaded into the opening and is maintained against displacement by a dowel screw 26. The inner end of the spring 23 abuts 15 a spring follower 27 which is slidably mounted in the casing 24 and which is secured to one end of a tubular member 28. The adjacent end of the rack bar 12 is provided with a reduced portion 29 adapted to project within the tubular member 28 with a shoulder 30 formed on the rack bar in abutting engagement with the follower 27.

The outer end of the casing 24 is closed by a head or cap 31 which is formed with a reduced inwardly extending portion 32 and an outwardly extending reduced portion 33. The cap 31 is also formed with an axial bore 34 in which the outer end of the tubular member 28 is slidably mounted and which is closed 30 at its outer end by a threaded plug 35. It will be noted that the pressure exerted by the spring 23, at all times tends to hold the parts in the positions shown in Fig. 4 in which the trackway trip arm 10 occupies an upright or 35 operative position. It is apparent that the fluid pressure in the cylinder 14 must be sufficient to overcome the pressure of the spring 23 in order to swing the arm 10 to an inoperative position to permit the uninterrupted 40 passage of a train over the trackway.

If, for any reason, it should be necessary to remove the casing 24 and spring 23, such as for replacement or repairs, the screw plug 35 is first removed and a bolt 36 (Fig. 5) inserted through the bore 34 and screwed into the internally threaded inner end 37 of the tubular member 28. The bolt 36 is provided with a washer 38 for abutting engagement with the reduced portion 33 of the cap so that when the bolt 36 is tightened it will draw the tubular member 28 and follower 27 outwardly, thus confining the spring 23 under compression within the casing 24 between the cap 31 and the follower 27 and relieving 45 the pressure on the rack bar 12. This permits the casing and spring to be removed from and replaced on the housing 1 as a unit. This feature not only prevents the spring 23 from causing the screw threads to bind, but eliminates the danger of the casing being suddenly projected from the housing under the action of the spring 23 when the casing is being removed, and the possibility of injury to the repair man. Also, this improvement 50 eliminates the necessity of compressing the

relatively strong spring 23 manually in assembling the device and holding it under compression while effecting the threaded connection between the casing 24 and the housing 1. Were it not for the above described construction, the spring 23 would project some distance out of the casing when relaxed and would require considerable exertion to compress it back within the casing by forcing the follower against the reduced end of the rack 55 bar in assembling the device.

The device also embodies a circuit controller for establishing certain electric circuits according to the position occupied by the trackway trip arm. This controller is 60 contained in a chamber 39 formed in the housing 1 (Figs. 3, 6 and 7) and to which access may be conveniently had through a removable cover 40. A support or table 41 (Figs. 6 and 7) is mounted within the chamber 39 65 by bolts 42, and carries a pair of insulating blocks 43^a and 43^b arranged in spaced parallel relation. Two sets of electrical contact members 44^a and 44^b are mounted on the block 43^b and are adapted to be engaged by 70 two sets of spring contact fingers 45^a and 45^b of corresponding number which are mounted on the block 43^a.

In one position of the apparatus the fingers of one set are simultaneously flexed out of engagement with their respective contacts and in another position of the apparatus, the fingers of the other set are simultaneously moved into engagement with their associated contacts, in order to open certain electric 75 circuits and to establish other desired circuits, by means of a pair of blocks 46^a and 46^b of insulating material which are mounted 80 between the blocks 43^a and 43^b for longitudinal movement. These blocks 46^a and 46^b 85 are each provided with a plurality of pairs of vertically extending pins 47^a and 47^b for engagement with opposite sides of each of the contact fingers. The blocks 46^a and 46^b 90 are carried by slides 48^a and 48^b (Figs. 6 and 7) which are mounted on the table 41 with the edges thereof projecting beneath the edges of the stationary insulating blocks 43^a and 43^b in order to prevent their vertical displacement. The slides 48^a and 48^b are provided with depending studs 49^a and 49^b, which 95 project downwardly through openings 50^a and 50^b formed in the table 41, and which studs are formed with substantially spherical lower extremities 51^a and 51^b for engagement with cylindrical bores 52^a and 52^b formed in the upper ends of a pair of levers 53^a and 53^b. These levers are pivotally mounted, as indicated at 54^a and 54^b, on the housing 1, and on opposite sides of a shaft 100 55 which is disposed in axial alignment with the shaft 4.

Said shaft 55 is journaled at its outer end in a bearing 56 formed in the housing 1, and at its inner end in the bearing 5, and is con- 105

nected with the shaft 4 at this point, so as to rotate therewith, by means of a spline coupling 57. A cam 58 is fixed to the shaft 55 adjacent the bearing 56, and, in addition to its functions presently to be described, prevents the shaft 55 from moving out of engagement with the shaft 4. This cam is formed with a pair of substantially diametrically disposed cam lobes 59^a and 59^b. The 5 lobe 59^a co-operates with a pair of anti-friction rollers 60^a and 61^a carried by the lever 53^a, and the lobe 59^b co-operates with a pair of similar rollers 60^b and 61^b carried by the 10 lever 53^b.

15 From the foregoing it will be apparent that with the parts occupying the positions shown in Fig. 3, in which the contacts 44^b—45^b are closed and the contacts 44^a—44^b are open, when the shaft 55 and cam 58 carried 20 thereby are rocked in a counter-clockwise direction, as indicated by the arrow in Fig. 7, the cam lobe 59^b acting on the roller 60^b will first swing the lever 53^b about its pivot 54^b in a clockwise direction and shift the slide 25 48^b and block 46^b carried thereby to the right, through the means of the telescopic connection between the lever 53^b and the stud 49^b. This movement of the block 46^b will cause the pins 47^b carried thereby to flex all 30 of the spring contact fingers 45^b out of engagement with their associated contacts 44^b, thus opening all of the circuits therethrough. This initial rotary movement of the cam 58 does not immediately actuate the lever 53^a 35 as the roller 60^a occupies a position intermediate the ends of the cam lobe 59^a and consequently the contacts 44^a—45^a still remain open. The continued rotation of the shaft 55 and cam 58, however, carries the cam lobe 59^a out of engagement with the roller 60^a of 40 the lever 53^a and into engagement with the roller 61^a, thus causing the lever 53^a to rock about its pivot 54^a and shift the slide 48^a and block 46^a to the right, carrying 45 the spring fingers 45^a into engagement with their associated contacts 44^a. Conversely, when the shaft 55 and cam 58 are rocked in the opposite direction, that is to say, in a clockwise direction, as viewed in Fig. 7, the 50 contacts 45^a—44^a are first opened and after a short interval of time the contacts 45^b—44^b are closed. It will be noted that there is an interval of dwell during which the circuits through all of the contacts are open, regardless of the direction of rotation of the cam 58.

55 When the parts occupy the positions illustrated in the drawing, in which the trackway trip arm 10 is held in an upright operative position under the action of the spring 23, the fact is indicated in any suitable manner by circuits established through the contacts 44^b—45^b. When, however, it is desired to move the trackway trip arm 10 to an inoperative position so as to permit of the passage 60 of a train, fluid pressure is admitted to the

cylinder 14. This forces the piston 19 and the rack bar 12 to the left, as viewed in Fig. 4, against the action of the spring 23 and rocks the segmental gear 11 and shaft 4 in a counter-clockwise direction an amount sufficient to 70 swing the trackway trip arm to a substantially horizontal position. The parts are so proportioned that the arm 10 is swung through an arc of necessary magnitude notwithstanding the relatively small travel of 75 the piston 19. This counter-clockwise rotation of the gear 11 and shaft 4 rotates the shaft 55 and cams 8 (Fig. 7) also in a counter-clockwise direction. As soon as the movement of the cam commences the lever 53^b 80 opens all of the contacts 44^b—45^b, as previously described. As the shafts 47 and 35 approach the limit of their rotary movement and the arm 10 approaches its horizontal inoperative position, the cam operates 85 the lever 53^a to close all of the contacts 44^a—45^a. It will be noted in this connection that while the contacts 44^b and 45^b are opened simultaneously with the beginning of the 90 above described movement of the parts, the contacts 44^a—45^a are not operated until the trip arm has practically completed its movement to an inoperative position. If the supply of fluid pressure to the cylinder 14 is 95 interrupted the parts will return to the positions in which they are illustrated in the drawing under the influence of the spring 23. During the return movement of the parts the cycle of operations previously described is 100 performed in a reverse order, as will be apparent from the drawings.

105 It sometimes occurs that the distance between the operating part of the train carried governing instrumentality and the trip arm varies, by reason of a reduction in the diameter of the wheels of the locomotive or car carrying such instrumentality, or a reduction in the height of the tread of the rails of the trackway, or both, due to wear. I have provided for such contingency so as to insure 110 that the trip arm will at all times be engaged properly by the element controlling the operation of the train carried governing means, in the following manner. The trip arm 10 is preferably formed with a pair of oppositely extending flanges 62 (Figs. 8 and 9) adjacent its lower end, which flanges are secured to a bar 63 disposed on one side of the shaft 7, by means of bolts 64. These bolts pass 115 through a bar 65 on the other side of the shaft and securely clamp the several parts together and to the shaft. A plurality of shims or plates 66 are interposed between the flanges 62 of the arm 10 and the bar 63, and these shims may be increased or decreased in number in order to lengthen or shorten the effective length of the arm. The portion of the shaft 7 on which the arm 10 is mounted is 120 preferably squared, and fits within recesses 67 and 68 formed in the bars 63 and 65, thus not 125 130

only preventing the arm from turning on the shaft but also maintaining it against movement transverse to the axis of the shaft. The arm 10 may be secured to the shaft in any one of several longitudinal positions, in order to adjust it accurately in a direction transverse of the trackway, by means of a set screw 69 which is threaded into the bar 65 for engagement with one of several apertures 70 drilled in the shaft 7, as best shown in Fig. 9.

From the foregoing, it will be apparent that I have provided a very simple, yet rugged train stopping device, which can be assembled and dissembled with minimum time and effort and which eliminates from its construction many connecting elements such as pins and the like, thereby materially increasing the factor of safety.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway traffic governing device comprising a rotatable shaft, a casing open at one end and closed at the other and removably attached at its open end to said device, a spring disposed within said casing for rocking said shaft in one direction, means for rocking said shaft in the other direction against the action of said spring, and means for rendering said spring inactive and confining it within said casing to permit said casing and spring to be secured to and removed from said device as a unit.

2. In combination, a railway traffic governing device comprising a rotatable shaft, a casing open at one end and closed at the other and removably attached at its open end to said device, a spring disposed within said casing for rocking said shaft in one direction, means for rocking said shaft in the other direction against the action of said spring, and means actuated from the exterior of said casing for rendering said spring inactive and confining it within said casing to permit said casing and spring to be secured to and removed from said device as a unit.

3. In combination, a railway traffic governing device comprising a housing, a movable element mounted in said housing, means for operating said element in one direction, a casing open at one end and closed at the other and removably attached at its open end to said housing, a compression spring in said casing for operating said element in another direction, and means for maintaining said spring under compression and within said casing to permit said casing and spring to be

mounted on and removed from said housing as a unit.

4. In combination, a railway traffic governing device comprising a housing, a rock-shaft journalled in said housing, means for rocking said shaft in one direction, a casing open at one end and closed at the other and removably attached at its open end to said housing, a compression spring in said casing for rocking said shaft in the other direction, and means for preventing said spring from expanding out of said casing when said spring and casing are removed as a unit from said housing.

5. In combination, a railway traffic governing device comprising a housing, a rock-shaft journalled in said housing, means for rocking said shaft in one direction, a cylindrical casing removably mounted on said housing, a tubular cap mounted on one end of said casing, a spring follower slidably mounted in said casing adjacent the other end thereof, operative connections between said follower and said shaft, a compression spring mounted within said casing intermediate said cap and said follower for rocking said shaft in the opposite direction, and means insertable through said cap for preventing said follower from moving under the action of said spring to permit said casing and said spring to be secured to and removed from said housing as a unit.

6. In combination, a railway traffic governing device comprising a housing, a rock-shaft journalled in said housing, means for rocking said shaft in one direction, a cylindrical casing removably mounted on said housing, a tubular cap mounted on one end of said casing, a spring follower slidably mounted in said casing adjacent the other end thereof, operative connections between said follower and said shaft, a compression spring mounted within said casing intermediate said cap and said follower for rocking said shaft in the opposite direction, and means extending through said cap and engageable with said follower for locking said follower against movement under the action of said spring to permit said casing and spring to be secured to and removed from said housing as a unit.

7. In combination, a railway traffic governing device comprising a housing, a rock-shaft journalled in said housing, means for rocking said shaft in one direction, a cylindrical casing removably mounted on said housing, a tubular cap mounted on one end of said casing, a spring follower slidably mounted in said casing adjacent the other end thereof, operative connections between said follower and said shaft, a compression spring mounted within said casing intermediate said cap and said follower for rocking said shaft in the opposite direction, and means extending through said cap and engageable with

said follower for maintaining said spring under compression within said casing to permit said casing and spring to be secured to and removed from said housing as a unit.

8. In combination, a railway traffic governing device comprising a housing, a rock-shaft journalled in said housing, a trackway trip arm carried by said shaft, means for rocking said shaft in one direction, a cylindrical casing removably mounted on said housing, a tubular cap mounted on one end of said casing, a spring follower slidably mounted in said casing adjacent the other end thereof, operative connections between said follower and said shaft, a spring mounted within said cylinder intermediate said cap and said follower for rocking said shaft in the opposite direction, a member extending co-axially through said spring and having one end 20 thereof secured to said follower and the other end thereof slidably mounted in said cap, and means for preventing said member from sliding in said cap under the action of said spring to permit said spring and casing to be secured 25 to and removed from said housing as a unit.

9. In combination, a railway traffic governing device comprising a housing, a rock-shaft journalled in said housing, means for rocking said shaft in one direction, a cylindrical casing removably mounted on said housing, a tubular cap mounted on one end of said casing, a spring follower slidably mounted in said casing adjacent the other end thereof, operative connections between said follower and said shaft, a compression spring mounted within said casing intermediate said cap and said follower for rocking said shaft in the opposite direction, a tube extending co-axially within said spring and having one 30 end thereof secured to said follower and the other end thereof slidably mounted in said cap, and means extending through said cap for engagement with said tube for maintaining said spring under compression to permit 35 said spring and casing to be secured to and removed from said housing as a unit.

10. In combination, a railway traffic governing device comprising a housing, a rock-shaft journalled in said housing, means for 40 rocking said shaft in one direction, a cylindrical casing removably mounted on said housing, a tubular cap mounted on one end of said casing, a spring follower slidably mounted in said casing adjacent the other end thereof, operative connections between said follower and said shaft, a compression spring mounted within said casing intermediate said cap and said follower for rocking said shaft in the opposite direction, a tube extending co- 45 axially within said spring and having one end thereof secured to said follower and the other end thereof slidably mounted in said cap, and a bolt extending through said cap and having a screw-threaded engagement with said 50 tube for maintaining said spring under com-

pression to permit said spring and casing to be secured to and removed from said housing as a unit.

11. In combination, a railway traffic governing device comprising a housing, a rock-shaft journalled in said housing, a trackway trip arm carried by said shaft, a gear fixed to said shaft, a reciprocable rack bar mounted for intermeshing engagement with said gear, a fluid pressure cylinder mounted on said housing, a piston in said cylinder and in operative engagement with one end of said rack, means for admitting fluid pressure to said cylinder to move said rack in one direction, a cylindrical casing mounted on said housing in axial alignment with said fluid pressure cylinder, a follower slidably mounted in said casing and in operative engagement with the other end of said rack and a spring in said casing for moving said rack in the other direction. 70

12. In combination, a railway traffic governing device comprising a housing, a rock-shaft journalled in said housing, a trackway trip arm carried by said shaft, a gear fixed to said shaft, a reciprocable rack bar mounted for intermeshing engagement with said gear, a fluid pressure cylinder mounted on said housing, a piston in said cylinder and connected with one end of said rack, means for admitting fluid pressure to said cylinder to move said rack in one direction, a cylindrical casing mounted on said housing in axial alignment with said fluid pressure cylinder, a follower slidably mounted in said casing and in abutting engagement with the other end of said rack, and a spring in said casing for moving said rack in the other direction. 80

13. In combination, a railway traffic governing device comprising a housing, a rock-shaft journalled in said housing, a trackway trip arm carried by said shaft, a gear fixed to said shaft, a reciprocable rack bar mounted for intermeshing engagement with said gear and having a substantially spherical head, a fluid pressure cylinder mounted on said housing, a piston mounted in said cylinder and provided with a reentrant seat adapted to be engaged by the spherical head of said rack 105 bar, means for admitting fluid pressure to said cylinder to move said rack bar in one direction, and a spring for moving said rack bar in the other direction. 110

14. In combination, a railway traffic governing device comprising, a housing, a rock-shaft journalled in said housing, a trackway trip arm carried by said shaft, means for rocking said shaft in opposite directions to swing said arm between operative and inoperative positions, a controller having a plurality of electrical contacts, a pair of slides each operatively connected with certain of said contacts, a stud extending from each of said slides, a lever slidably engaging each of 120

125

130

said studs, and a cam carried by said rock-shaft for swinging said lever and actuating said slides to selectively open and close certain of said contacts.

15. In combination, a railway traffic governing device comprising a housing, a rock-shaft journalled in said housing, a trackway trip arm carried by said shaft, means for rocking said shaft in opposite directions to swing said arm between operative and inoperative positions, a controller having a plurality of electrical contacts, a pair of slides each operatively connected with certain of said contacts, a stud extending from each of said slides and each terminating at substantially spherical extremities, a pair of levers pivotally mounted on said housing on opposite sides of said rockshaft and each provided with a cylindrical bore for telescopic engagement with the spherical extremity of one of said studs, and a cam carried by said rockshaft for positively rocking said levers in both directions to shift said slides successively and to selectively open and close certain of said contacts.

20. In combination, a railway traffic governing device comprising a housing, a rock-shaft journalled in said housing, means for rocking said shaft in opposite directions, a multi-part trackway trip arm carried by said shaft, and means insertable between the parts of said arm to vary the length thereof.

25. In combination, a railway traffic governing device comprising a housing, a rock-shaft journalled in said housing, means for rocking said shaft in opposite directions, a multi-part trackway trip arm carried by said shaft, said arm comprising a portion provided with oppositely extending flanges adjacent to its inner end, a pair of bars engageable with opposite sides of said shaft, a plurality of shims interposed between the flange portion of said arm and one of said bars and a plurality of bolts extending through said flanges, shims and straps on opposite sides of said shaft and securing them together and to said shaft, one or more of said shims being adapted to be removed to vary the effective length of said arm.

30. In combination, a railway traffic governing device comprising a housing, a rock-shaft journalled in said housing and having a square extremity, means for rocking said shaft in opposite directions, a pair of bars each having a recess provided therein adapted to engage opposite sides of the squared portion of said shaft, a trackway trip arm, and a plurality of bolts extending through said bars on opposite sides of said shaft and securing said bars and trip arm together and to said shaft.

35. In combination, a railway traffic governing device comprising a housing, a rock-shaft journalled in said housing and having a plurality of spaced apertures provided in one

end thereof, means for rocking said shaft in opposite directions, a pair of bars disposed on opposite sides of said shaft, a trackway trip arm, a plurality of bolts extending through said bars on opposite sides of said shaft and securing said bars and trip arm together and to said shaft, and a set screw threaded into one of said bars for engagement with one of the apertures in said shaft to prevent relative movement between said arm and shaft.

In testimony whereof I affix my signature.

JOHN P. COLEMAN.
